Tristram Burges, & Simeon Burges, of Livonia, N.Y.
Letters Patent

The schedule referred to in these Letters Patent, and making part of the same, containing a description in the words of the said Tristram Burges, & Simeon Burges, themselves, of their improvement in making Truss Hoops.

To all to whom these presents shall come: Be it known, that we, Tristram Burges, & Simeon Burges, of the Town of Livonia, County of Livingston & State of New-York, have invented a new & useful improvement in making Truss hoops, and that the following is a full & exact description of the construction & operation of said machine, as invented by us, to wit—

Fig 1st. A. the base on which the machine stands; B. two perpendicular post, that support the Cylinder. C. the cylinder on which the hoops are drawn by lever power the inside lap or first end of the hoop is made fast in the cylinder either with a key, box or screw, or some more sure & convenient way. D. the channel or groove to fasten the first end of the hoop in. E. the channel or groove to receive the gripe that holds or confines the hoop until riveted. F. the mortice in the cylinder between the two posts, to receive the lever to turn the cylinder. G. the slide passing through the post, gives the size of the hoop. H. the screw that confines the slide in its proper place. I. the roller, with a flange on one end to guide the hoop when rolling on to the cylinder. J. the stirrup within which the above described roller moves. K. the spring that presses the roller hard on the hoop. L. the balance key that confines the spring to its proper place. M. a small steel spring to raise the stirrup & roller off the hoop. — Fig 2nd. A. cylinder made of iron, brass or some suitable material made the same taper of the cylinder above described for the purpose of heating & rounding the hoop, after riveting, to wit. A. the largest end of the cylinder. B. the smallest end of the cylinder. C. the conical or tapering sides of the cylinder. And further we call the two cylinders above described, with their various operations, our principle—

Witness, our hands 22^d Decr 1834
